AEROSOL CAN OR SIMILAR ARTICLE

Edward W. Sexton, Jr., Boston, Mass., assignor to Sexton Can Company, Inc., Everett, Mass., a corporation of Massachusetts

Filed Aug. 26, 1968, Ser. No. 13,257

Term of patent 14 years

Int. Cl. D9—01
U.S. Cl. D9—9

FIG. 1

FIG. 2

FIGURE 1 is a perspective view of an aerosol can embodying my new design; and

FIGURE 2 is a side elevation view thereof.

The characteristic feature of my design resides in the combination near the top of the aerosol can shown of a first bulge formed by a concave lower surface which extends upwardly and outwardly from the cylindrical body of the can to the apex of the bulge and a convex upper surface which extends upwardly and inwardly from the apex of the first bulge and merges smoothly into an upwardly and inwardly extending surface which forms the base of a second bulge which is located a substantial distance inwardly from the cylindrical body of the can.

I claim:

The ornamental design for an aerosol can or similar article, substantially as shown and described.
